UNITED STATES PATENT OFFICE.

CHARLES E. SKELTON, OF SYRACUSE, NEW YORK, ASSIGNOR TO RANDOMTEX DYE-
ING MACHINE CORPORATION, OF SYRACUSE, NEW YORK, A CORPORATION OF
NEW YORK.

PERFORATING DEVICE FOR CONES.

Application filed March 12, 1925. Serial No. 14,954.

This invention relates to a paper cone perforating device of the class set forth in a pending application, Serial #751,070, filed November 20, 1924, in which a hollow paper or equivalent cone is used as the supporting medium for a bobbin of yarn or other thread to facilitate the coloring of portions of the yarn and mass by drawing the coloring matter through the porous mass of yarn by means of a suction device inserted into or connected to the perforated core in a manner somewhat similar to that shown in a pending application, Serial No. 751,069, filed November 20, 1924.

It will be evident, however, that the same device may be used for perforating other objects without departing from the spirit of the invention.

The main object is to provide a simple and efficient means for expeditiously perforating hollow fibrous objects such as paper cones either before or after yarn has been wound thereon and preparatory to coloring portions of the yarn en masse without removing it from the cone.

Another object is to provide simple and efficient means whereby the operation of the punching elements may be controlled by fluid pressure from any available source, not shown.

Other objects and uses relating to specific parts of the device and its controlling means will be brought out in the following description.

In the drawings:

Figure 1 is a longitudinal, vertical sectional view of a perforating device embodying the features of my invention.

Figure 2 is an enlarged, transverse, sectional view taken in the plane of line 2—2, Figure 1.

Figure 3 is an enlarged, horizontal sectional view through the controlling valve taken in the plane of line 3—3, Figure 1.

As illustrated, this perforating device comprises a sleeve —61— mounted in the upper portion of an upright bracket —3— of a main-supporting frame —3— to extend beyond the offset ends of said bracket for receiving at its rear end a collar —62— and at its front end a tapered head —63— corresponding approximately to the size and form of the interior of the tapered core or bobbin —a— which is adapted to be placed thereon

and removed therefrom by endwise sliding movement, the conical core —a— being adapted to receive and support a mass of yarn —A— wound thereon.

The inner ends of the collar —62— and tapered head —63— abut against the adjacent end faces of the bearing —3'— and are secured by set screws —64— and —65— to the corresponding ends of the sleeve —61—, Figure 1.

A cylinder —66— is secured to the outer end of the collar —62— co-axial with the sleeve —61— and is provided with a piston chamber —67— for receiving a piston —68— which is movable endwise therein by air pressure as will be presently described.

The piston —68— is connected to a rod —69— which extends through and beyond the opposite end of the sleeve —61— and is provided with an axially adjustable head —70— and axially spaced shoulder —71— and —72— and axially spaced conical bearing —73— and —74—, the head —70— being also provided with a lengthwise peripheral key-way —75— for receiving a key —76— on the tapered head —63— for locking those two parts against relative rotary movement while permitting axial movement of the head —70— within the member —63—. Associated with each of the tapered portions —73— and —74— are separate sets of 85 perforating pawls or levers —77— and —78— pivoted respectively at —79— and —80— to the head —63— and adapted to move in radial slots —81— and —82— in the head —63—.

The levers —77— and —78— of each set are arranged in uniformly spaced relation circumferentially of the head —63—, the heels of the levers —77— being engaged with the shoulder —71— on the head —70— 95 while the heels of the levers —78— are engaged with the shoulder —72— of said head whereby the rearward movement of the head —70— will cause the opposite ends of all of the levers to be drawn inwardly within the 100 periphery of the head —63—, thus permitting the conical core —a— with the yarn wound thereon to be readily pressed upon said head by rearward sliding movement thereon.

The front ends of the levers —77— and —78— are respectively provided with pointed perforating members or punches

—83— and —84— projecting outwardly therefrom, the inner edges of said pawls being engaged respectively with the tapered portions —73— and —74— of the head —70— so that when the core —a— of the bobbin is pressed on the mandrel —63— and the head —70— is moved forwardly by the piston —63— the perforating points or punches —83— and —84— will be simultaneously forced outwardly through the surrounding portion of the core —a— for perforating the latter, after which the head —70— is returned rearwardly by the return movement of the piston —63— to withdraw the perforating points —83— and —84— within the periphery of the mandrel —63— to allow the perforated core —a— with the yarn wound thereon to be withdrawn from the mandrel —63— ready for a repetition 20 of the operation just described upon another perforated core.

Piston operating means.

A fluid pressure pipe —88— leading from 25 air compressor or any other available source of fluid pressure supplied, not shown, is operatively connected to a valve case —90— on the main frame —3— so as to discharge the compressed air or other fluid under pressure directly over an oscillator disk valve —91— and to normally exert pressure upon said valve toward its seat —92— and thereby to exhaust a coiled spring —93— in maintaining an air-tight joint between 30 the valve and its seat to prevent accidental shifting of the valve rotarly.

The bottom of the valve case —90— is provided with separate diametrically opposite ports —94— and —94'— connected by pipes —95— and —95'— to separate ports —96— and —96'— in the ends of the cylinder —66— at opposite ends of the piston —68—, said valve seat —92— being also provided with an exhaust port —97— arranged substantially midway between the ports —94— and —94'— circumferentially and substantially the same distance from the center of oscillation of the valve —91—.

The valve —91— is also provided with 50 separate ports —98— and —98'— at one side of its axis, and a circumferentially elongated passage —99— at the opposite side of said axis, the passage —99— being provided with ports —100— and —101— at the ends thereof and opening through the bottom of the valve, the top and bottom of the passage between the ports —100— and —101— being closed.

The ports —98— and —98'— and —100— 60 and —101— are arranged circumferentially around the axis of the valve in uniformly spaced relation equal distances from said axis corresponding to the radial distances of the ports —94— and —94'— from the same axis so that when the port —98— of

the valve —91— is registered with the port —94'— in the bottom of the valve case the port —100— will be registered with the exhaust port —97— at the same time that the port —101— is registered with the port —94—, thus permitting the passage of the compressed air from the pipe —88— into the valve chamber above the valve and thence through the registering ports —98— and —94'— and pipe —95'— to the port —96'— for operating the piston —68— and head —70— rearwardly and thereby withdrawing the perforating levers —77— and —78— inwardly.

During this operation of the piston by 80 the compressed air the air at the rear end of the piston will be exhausted through the pipe —95— and ports —94— and —101— and thence through the elongated passage —99— and out through the registering ports —100— and —97— to the atmosphere, Figure 1.

Now by turning the valve —91— through the medium of its operating handle —91'— in the direction indicated by the arrow —x—, 90 Figure 3, then by turning the valve one-quarter turn the ports —100— and —101— will be registered respectively with the ports —94'— and —97— while the port —98'— will be moved to the position occupied by the port —98—, under which conditions the compressed air admitted to the valve chamber through the pipe —88— will pass through the then registering ports —98'— and —94— and thence through the pipe —95— to the port —96— at the rear end of the piston for moving said piston forwardly and thereby forcing the punching levers —77— and —78— outwardly for perforating the core —a—.

During this forward movement of the piston and while the valve remains in its last adjusted position the air at the front of the piston will be exhausted through the pipe —95'— and thence through the registering ports —94'— and —97— to the atmosphere, it being understood that the port —98— will then be closed by the underlying portion of the valve case —92—.

The construction and operation of my invention will now be readily understood upon reference to the foregoing description and accompanying drawings and while the construction shown and described is particularly efficient it is evident that various changes may be made in the detailed construction and operation without departing from the spirit of this invention.

What I claim is:

1. A device for perforating the hollow 125 paper cones of yarn bobbins comprising a head tapered to correspond to the taper of the cone for receiving and supporting said cone, a punch movable through an opening in the tapered portion of the head for per-

forating the cone hereon, and means reciprocally movable within the head for operating the punch.

2. A device for perforating the hollow conical cores of yarn bobbins comprising a head tapered to correspond to the taper of the core and provided with radial openings extending through the periphery thereof, levers pivoted to said head and provided with punches movable in said openings for perforating the core on the head and means reciprocally movable within the head for operating said levers.

3. A device for perforating the paper conical cores of yarn bobbins comprising a head tapered to correspond to the taper of the core for receiving and supporting said core, separate sets of punches arranged at different points along the axis of the head and movable through openings in the periphery of said head, and means reciprocally

movable within the head for operating the punches of both sets simultaneously.

4. A device for perforating cones comprising a tapered support for the cone having radial slots extending through the tapered peripheral surface, and punches registering with said slots and movable radially for perforating the cone thereon.

5. A device for perforating hollow paper cones comprising a supporting head tapered to conform to the interior taper of the cone and provided with a radial opening, a bell crank lever mounted on the head and having one arm provided with a punch registering with said opening and movable radially for perforating the paper cone on the head, and reciprocally movable means coaxial with the head for operating said lever.

In witness whereof I have hereunto set my hand this 9th day of March, 1925.

CHARLES E. SKELTON.
